UNITED STATES PATENT OFFICE

102,383

DESIGN FOR A CABINET FOR AN AIR CONDITIONING UNIT OR SIMILAR ARTICLE

Allen P. Livar, Yonkers, N. Y.

Application September 21, 1936, Serial No. 64,945

Term of patent 7 years

To all whom it may concern:

Be it known that I, Allen P. Livar, a citizen of the United States, residing at 830 Bronx River Road, Yonkers, in the county of Westchester and State of New York, have invented a new, original, and ornamental Design for a Cabinet for an Air Conditioning Unit or Similar Article, of which the following is a specification, reference being had to the accompanying drawings, forming part thereof.

Referring to the drawings:

Figure 1 is a perspective view of the cabinet showing my new design,

Figure 2 is a top plan view thereof,
Figure 3 is a rear elevational view thereof,
Figure 4 is an end elevational view thereof, and
Figure 5 is a fragmentary cross-sectional view on an enlarged scale, taken on line 5—5 of Fig. 1, the section being broken away for convenience of illustration.

I claim:

The ornamental design for a cabinet for an air conditioning unit or similar article substantially as shown and described.

ALLEN P. LIVAR.
